UNITED STATES PATENT OFFICE.

JOHN F. MEIGS AND ROBERT P. STOUT, OF SOUTH BETHLEHEM, PENNSYLVANIA, ASSIGNORS TO BETHLEHEM STEEL COMPANY, OF SOUTH BETHLEHEM, PENNSYLVANIA.

RECOIL-CHECK.

SPECIFICATION forming part of Letters Patent No. 763,775, dated June 28, 1904.

Application filed January 30, 1900. Serial No. 3,329. (No model.)

To all whom it may concern:

Be it known that we, JOHN F. MEIGS and ROBERT P. STOUT, of South Bethlehem, in the county of Northampton, and in the State of Pennsylvania, have invented certain new and useful Improvements in Recoil-Checks; and we do hereby declare that the following is a full, clear, and exact description thereof, reference being had to the accompanying drawings, in which—

Figure 1 is a top plan view of a gun and carriage embodying our invention in firing position; Fig. 2, a side elevation thereof with the near carrying-wheel removed; Fig. 3, an end elevation looking from the breech end of the gun; Fig. 4, a longitudinal section through one of the recoil-controlling mechanisms, and Fig. 5 a cross-section thereof.

Letters of like name and kind refer to like parts in each of the figures.

The object of our invention is to provide a light and compact recoil-controlling mechanism for ordnance; and to this end our invention consists in the mechanism having the features of construction substantially as hereinafter specified.

In the embodiment of our invention selected for illustration a carriage is employed mounted on wheels A and A and axle B, the gun C being supported from the axle by two frames D and D, secured to the axle at opposite sides of the gun. Extending parallel with the gun-axis at each side of the gun is a tube E, that is fastened rigidly to and forms a part of the frame D, each end of the tube being threaded exteriorly and passed through an opening in the frame end, to which latter it is clamped by nuts e and e, screwed on the tube on opposite sides of the frame end. The nut on the outer side forms a cap or closure for the end of the tube. Mounted slidably upon each tube E is a cylinder F, that has a bearing or journal for a gun-trunnion c. Between said cylinder and the tube is an annular fluid-holding space, the ends of the cylinder being closed in a familiar way, so as to be fluid-tight, and on the tube E at or near mid-length is an annular enlargement e', that closely fits the cylinder

and constitutes a piston therefor, the tube E being thus a piston-rod as well as an important part of the gun-supporting frame. Within the tube or piston-rod F at or near mid-length is screwed a sleeve G, having two oppositely-facing valve-seats for two valves H and H, mounted slidably upon a bolt or rod I, that is supported by disks K and K at opposite ends of the sleeve G. A piston L is in the tubular piston-rod E on each side of the sleeve G, and interposed between the same and the nearer closed end of said piston is a coiled spring M, that yieldingly holds said piston adjacent to the sleeve end. Channels or passages N and N place the annular space in the cylinder in communication with the space between the two valves, and the disks K and K are perforated to establish communication between the spaces on opposite sides of each. It will be seen that when the gun recoils the cylinders F and F will move with it over the pistons e and e', forcing the liquid from each cylinder into the space between the valves and causing it to move both from their seats and to move the pistons L and L in opposite directions, compressing the springs M and M for producing counter-recoil, to permit which the valves are provided with minute openings for the return of the liquid to the cylinder. By the utilization of the cylinders as the gun-supports, and the employment of the piston-rods as the slides on which the gun-supporting cylinders move and as the housings for the springs and by the arrangement of the springs, there is great gain both in compactness and reduction of weight.

Should it be found desirable to regulate the travel of the gun in recoiling by varying the flow of liquid through the channels N and N, this can be done by applying to the inner end of the piston a disk O, having for co-operation with each channel N a slot o of diminishing cross-section and automatically rotating the disk as the gun and cylinder move longitudinally, so as to present portions of the slot of varying cross-section opposite its channel N. A simple expedient for thus automatically turning the disk is a spiral groove

f in the wall of the cylinder and a lug or pin on the disk that engages such groove.

To limit the expansion of each of the springs M and M when for any reason the tube-closing nut *e* may be removed, there is placed within the tube a ring-form abutment P for the outer end of the spring, which abutment is mounted on the end of a support Q, fastened at its other end to the nearer piston L.

10 The support Q is jointed telescopically to permit a short expansion of the spring out of the tube.

It is to be understood that we do not restrict the use of our invention to a wheeled or 15 any other particular type of gun-carriage or mount.

Having thus described our invention, what we claim is—

1. The combination of a fluid-holding cylinder, a piston therein, a hollow piston-rod, a passage being provided for the fluid to pass from the cylinder into the said rod, a piston in said rod subjected to pressure from fluid forced through the passage from the fluid-holding cylinder, and yielding means to oppose movement of the piston in the rod when it is subjected to pressure from the fluid-holding cylinder, substantially as and for the purpose described.
- 20 2. The combination of a fluid-holding cylinder, a piston therein, a hollow piston-rod, and two oppositely-acting pistons in said rod, the fluid-holding cylinder being in commun- 25

cation with a space between the two pistons in the piston-rod.

3. The combination of a fluid-holding cylinder, a piston therein, a hollow piston-rod, pistons in said rod, movable in directions toward and from each other, a passage being provided for the fluid to pass from the cylinder to the rod to act on the pistons therein, and spring mechanism for moving the pistons oppositely to the direction of their movement under the fluid-pressure.

4. The combination of the piston, piston-rod and cylinder of a recoil mechanism, said piston-rod being hollow, a fluid-operated piston in the rod, and a counter-recoil spring in the rod acting on said piston, substantially as described.

5. In a recoil mechanism, the combination of a cylinder, a piston therein, a piston-rod that is hollow, pistons in said rod, having opposing faces exposed to pressure from the cylinder, and a spring for each of the pistons 55 that is within the piston-rod, substantially as and for the purpose described.

In testimony that we claim the foregoing we have hereunto set our hands this 13th day of January, A. D. 1900.

JOHN F. MEIGS.
ROBERT P. STOUT.
